FLUID STORAGE AND DISCHARGE APPARATUS
Richard T. Cornelius, Minneapolis, Minn., assignor to
The Cornelius Company, Anoka, Minn., a corporation
of Minnesota

Filed Mar. 8, 1962, Ser. No. 178,501
9 Claims. (Cl. 222—386.5)

This invention relates generally to fluid storage and discharge apparatus, and more particularly to an improved tank structure.

Although the principles of the present invention may be included in various tanks, a particularly useful application is made in a tank which is adapted to discharge its own contents. This result is obtained by the inclusion of means which divide the tank into two separate chambers, one of which contains the fluid to be dispensed, and the other of which is provided with a condensable gas. Upon the expansion of such gas, which is liquefied at the discharge pressure, the gas cools and must absorb heat from outside the chamber to reestablish the pressure.

In the structure shown in my Patent No. 2,513,455, the gas chamber is defined by a member which is so constructed that it must stretch in order to drive out or discharge substantially all of the stored fluid. It will be appreciated that many different types of fluid having various chemical properties can be stored and discharged by this apparatus, and that various condensable gases may be employed. However, not all materials are compatible with both the condensable gas and with the fluid, and since my prior structure required a diaphragm or member having elastic properties, the number of materials available for use in fabricating the movable member was quite restricted and limited.

Accordingly, it is an object of the present invention to provide an improved tank structure wherein the movable member may be constructed of material which is flexible, but which is not necessarily stretchable or elastic, thereby making available a considerably greater number of materials from which the structure may be fabricated.

The structure shown in my prior patent is particularly well adapted to be employed with such a gas and at such a temperature that a relatively high internal pressure is created. Such a rigid tank requires considerable labor to manufacture including expensive machining operations. Moreover, difficulty is sometimes encountered in assembling the movable member to the rigid parts in a gas-tight manner.

Accordingly, it is a further object of the present invention to provide an improved tank structure, the manufacture of which is inherently simplified and facilitated.

In a tank structure of the type described, there is a tendency for pockets to form between the flexible bag or diaphragm and the interior of the tank, within which pockets there would be entrapped a quantity of the fluid which is thus precluded from being discharged.

Accordingly, it is a still further object of the present invention to provide structure which acts to avoid actual entrapment of a fluid in any pocket.

Many other advantages, features and additional objects of the present invention will become manifest to those versed in the art upon making reference to the detailed description and the accompanying sheets of drawings in which a preferred structural embodiment incorporating the principles of the present invention is shown by way of illustrative example.

On the drawings:

FIGURE 1 is an elevational view of a tank structure constructed in accordance with the principles of the present invention;

2

FIGURE 2 is an enlarged cross-sectional view taken along line II—II of FIGURE 1, the movable member or diaphragm being broken away and illustrated partially in cross-section and partially in elevation;

5 FIGURE 3 is a view corresponding to the lower portion of FIGURE 2, with thicknesses represented by a single line and other details omitted for convenience, and which illustrates the cleaning, filling, and filled form of the device;

10 FIGURE 4 is similar to FIGURE 3 showing the upper portion of FIGURE 2, and representing the form of the device in an empty condition;

15 FIGURE 5 is an enlarged fragmentary cross-sectional detail of a portion of FIGURE 2, illustrating the position of the parts depicted as assembled;

FIGURE 6 is a fragmentary portion of FIGURE 5 illustrating the natural cross-sectional configuration of the portion depicted;

20 FIGURE 7 is a cross-sectional view similar to FIGURE 5, illustrating the position of the material depicted when the movable member is positioned as shown in FIGURE 4; and

25 FIGURE 8 is a cross-sectional view taken along line VIII—VIII of FIGURE 2, and both greatly enlarged and broken away.

As shown on the drawings:

The principles of this invention are particularly useful when embodied in a fluid discharge apparatus or storage and discharge tank such as illustrated in FIGURE 1, generally indicated by the numeral 10. The fluid discharge apparatus 10 includes a rigid tank 11 having appropriate feet 12, 13 at the opposite ends thereof for supporting the same with either end uppermost. Preferably the feet 12 and 13 are resilient and are directly bonded to the tank 11. As best seen in FIGURE 2, the rigid tank 11 comprises a pair of cup-shaped tank end portions 14, 15, one of which portions 14 has a fluid port 16 at one end of the tank, and the other of which end portions 15 has a gas port 17 at the opposite end of the tank. Each of the ports 16 and 17 is preferably provided with a valve 18, 19 respectively which communicates the interior of the ends of the tank 11 with the outside in a selective manner. The details of the valves 18 and 19 are conventional and form no part of this invention. As will be brought out more fully later herein, it is possible to build this device and to charge it with gas even though the port 17 and valve 19 were omitted. These elements are therefore optional and preferable.

50 The tank end portion 15 has a straight cylindrical section 15a which merges into a smooth concave portion 15b which jointly comprise an internal contour or configuration of the tank end portion 15. In like manner, the tank end portion 14 is provided with a similar internal contour or configuration. To that end, the tank end portion 14 includes a cylindrical section 14a which merges into a concave section or portion 14b which is apertured with a rather large oval-shaped opening 20. Within the opening 20 there is provided a rigid cover 21 having an oval O-ring 22 forming a seal between such cover 21 and a shoulder 23 provided in the opening 20 of the tank end 14. The internal contour of the rigid cover 21 comprises an extension of the contour of the tank end 14b so that the internal configuration of that end of the tank is generally or substantially the same as that of the opposite end. Where a boss 24 is provided to strengthen the support for the valve 18, it is preferable to include a slot or hole 25 to enable complete drainage of fluid. The rigid cover 21 is held in place by a manually actuated spring lever 26 which is rockably supported as at 27, 27 on the cover 21 and has end portions 28 which engage the outer surface of the tank. The cover

is further held closed by internal pressure. The details of the manually actuated spring mechanism 26 form no part of this invention.

The cup-shaped tank end portions 14, 15 abut each other at their mouths as shown in FIGURE 2, and as shown in enlarged detail in FIGURE 5. In the disclosed embodiment, the line of abutment is substantially at the axial center of the tank. Immediately within the line of abutment, there is provided a cylindrical ring 30, at one axial end 31 of which there is provided a rigid integral bead 32 or edge which projects axially toward the fluid end of the tank and which is disposed in radially inwardly spaced relation to the inner interior surface of the tank 11. It is thus apparent that the rigid bead 32 lies in a plane which is offset toward the end 14b from the axial center of the tank. A spotweld seam 33 extends about the tank and spans the line of abutment between the tank-end mouths and individually seals each of the tank end portions 14 and 15 to the cylindrical ring 30.

Also on the interior of the tank 11 there is provided a movable wall or diaphragm generally indicated at 34 which comprises molded flexible material such as rubber, it being understood that rubber is illustrative and that non-elastic materials or compounds of rubber, or those which are substantially so, may be employed with this structure. The diaphragm 34 divides the tank 11 into two chambers 35 and 36 which jointly have a constant volume, and the volume of each of which increases as the other decreases. Each of the chambers 35 and 36 is in direct heat transfer relation with the tank 11, and more specifically with the tank end portions 14 and 15 respectively.

The diaphragm 34 is provided with a periphery 37 which is offset in a direction toward the one end 14b from the axial center of the tank 11. The periphery 37, as best seen in FIGURE 5, includes an integral bead 38 or edge portion and tapered lip 39 adjacent to the bead 38. The tapered lip 39 has a free or "as-molded" position as shown in FIGURE 6, whereby when the same is assembled as shown in FIGURE 5, the tapered lip 39 forms a seal with the interior of the tank 11, the interior of the tank acting to confine the free diameter or tapered lip to a radially inwardly disposed position where it resiliently acts on the interior surface of the tank. The integral bead 38 is received between the rigid ring bead 32 and the adjacent interior surface of the tank 11, the bead 38 being slightly larger than the spacing through which it was received so as to positively hold it in assembled relation therewith.

As best seen in FIGURE 2, the periphery 37 of the diaphragm 34 tapers downwardly at 40 to form a thinner wall which extends in a cup-like manner, the bottom of the cup-shape being thickened. This structure enables the entire central portion 41 to be reversely deflected toward the end 14b as indicated in FIGURE 4 without elastic stretching of the diaphragm.

As best seen in FIGURE 2, the "as-molded" configuration of the central reversible portion is adjacent to the opposite end 15b, and in this condition has an effective axial length which is over one-half the total internal length or combined axial chamber lengths. Thus the central portion 41 can be reversed to the position shown in FIGURE 4, even if the flexible material of which the diaphragm is made is non-elastic. When so reversed, the structure shown in FIGURE 5 takes the position shown in FIGURE 7. It will be noticed that the tapered portion 40, being a zone of increased stiffness, tends to keep the reversing forces away from the tapered lip 39 and bead 38 so as not materially to affect the effectiveness of the seal formed thereby.

Where there is a pressure difference across the diaphragm 34 acting to deflect the same toward the tank end 15b such pressure difference places a tension on the peripheral joint illustrated in FIGURE 5 to seat the same more thoroughly. When the diaphragm 34 comprises

substantially non-elastic material, under such condition it will tend to retain the position illustrated in FIGURE 2. However, if the diaphragm 34 comprises rubber, as suggested herein, and is slightly elastic, it will deform to the position shown in single lines in FIGURE 3. As best seen in FIGURE 3, under such condition, the volume of the chamber 36 is very small. Moreover, the outer surface of the diaphragm 34 may engage the inner surface of the tank end 15 along the side portions 15a or end portion 15b. Thus the central portion 41 of the diaphragm 34 is conformable to the internal contour of the tank end 15. Similarly, when a higher pressure is present in the chamber 36, and the chamber 35 is empty, the opposite side of the central portion 41 will move into engagement with the interior of the tank end portion 14 and conform thereto, even if the diaphragm material is inelastic.

During engagement between the diaphragm and the interior of either end tank portion, there would tend to be a likelihood that pockets would be entrapped between the diaphragm and the inner wall of the tank. To preclude this possibility, the instant invention includes, preferably on each side of the diaphragm 34 as shown in FIGURE 2, a series of ribs 42 molded on the outside of the diaphragm 34, and a series of ribs 43 molded on the interior of the reversible central portion 41 of the diaphragm 34. The ribs 42 are thus engageable with the interior of the tank 11 when the diaphragm is arranged or deflected as shown in FIGURE 3, while the ribs 43 are engageable with the interior of the tank 11 when the diaphragm 34 is disposed or arranged as shown in FIGURE 4. As best seen in FIGURE 2, each of the ribs 42, 43 extends in a direction generally parallel to the axis of the tank or in a generally axially extending direction, and each of the ribs 42 and 43 converges near the port or toward the center. These ribs 42, 43 serve to vent any entrapped pocket which might tend to form when the diaphragm 34 is in its extremes of position as shown in FIGURES 3 and 4.

The chamber 36 is preferably filled with a proper charge of gas of a type which is condensable at the discharge temperature of the fluid in the chamber 33. The valve 19 is provided to admit such charge or to replenish such charge. The valve 19 also enables removal of the gas and replacement of it if so desired. During assembly of the device, before the cover 21 is in place and before the diaphragm 34 has been installed, the gas may be admitted through the opening 29 in liquid form, its temperature being reduced to the extent necessary to do so. Before the gas materially heats up, the diaphragm 34 may then be installed and the device as a whole is ready for filling with fluid, as by being pumped into the chamber 35 through the valve 18 against the pressure of the gas in the chamber 36 acting on the diaphragm 34. It is thus evident that in certain instances, it may be advantageous to omit the valve 19. It is also to be understood that this device may be sold as an article of commerce with the gas charge either included or omitted, so that the user could add a quantity and type of gas which would best suit his purpose.

Where the fluid discharge apparatus 10 is to be supported on a flat surface, and where connections are to be made to the valves 18 and/or 19, it is advantageous to include an opening 44 shown in FIGURES 1 and 2 through which appropriate lines may pass.

One of the apparent disadvantages of the use of rubber as a diaphragm material is that it has an odor which may be imparted to the fluid to be discharged. I have found that where such an odor is present, it may be completely removed by a normal washing process, such as may be employed to clean the chamber 35 prior to its being filled with the fluid. So long as the surface of the rubber which has been cleaned is not mechanically damaged, further giving off of an odor is precluded. Thus the odor appears to be largely a surface problem, and

any volatile materials which may remain within the rubber itself will not bleed through and give off a further odor. Such cleaning is advantageously carried out by applying a negative pressure or vacuum to the valve 19 to deflect the diaphragm 34 to the position shown in FIGURE 3, atmospheric pressure being on the opposite side of the diaphragm during such cleaning. When the cleaning has been completed, the fluid to be stored or dispensed may be added under atmospheric pressure to the chamber 35 through the opening 20, it being preferable to add such fluid by weight rather than by volume. Thereafter, the gas charge may be applied to the chamber 36, such charge being in the form of a liquid which fills the cup-shaped chamber 36 as insured by the ribs 42.

As explained in my prior patent, various gases may be employed depending upon the pressure desired and the discharge temperature which will most likely be employed. Examples include propane, sulphur dioxide, methyl chloride, butane, and dichloromonofluoromethane. At any event, when a desired discharge pressure has been determined, a gas having a corresponding condensation pressure at the discharge temperature chosen is selected.

With this invention, a substantially constant pressure is at all times maintained on the fluid to be discharged without the need for employing a pressure regulator or auxiliary source of gas. The gas may be reused and is not wasted, even if the valve 18 be left open. The instant structure will drain substantially completely even when the valve 18 is disposed upwardly, such drainage being complete if the valve 18 be disposed in a downwardly oriented attitude.

A further advantage of the instant invention is that it may be constructed in various sizes over a rather wide range. The instant embodiment disclosed herein is actually about nine and one-half inches in diameter and has a volume of about 576 fluid ounces in the chamber 35. The cup-shaped tank end portions 14 and 15 may comprise stainless steel having a thickness of 0.25 inch. A typical charge of condensable gas will be about 5 fluid ounces in the liquid form. Nevertheless, such a small charge will serve to drive the diaphragm from the position shown in FIGURE 3 to the position shown in FIGURE 4 while maintaining a constant discharge pressure, the absolute temperature of the gas charge remaining constant.

Although various minor modifications might be suggested by those versed in the art, it should be understood that I wish to embody within the scope of the patent warranted hereon all such embodiments as reasonably and properly come within the scope of my contribution to the art.

I claim as my invention:

1. Fluid discharge apparatus for discharging a fluid comprising:

- (a) a rigid tank having a fluid port at one end to receive and to discharge the fluid, and having a pressurizing port at the opposite end, said tank ends each having an internal contour; and
- (b) a molded reversible flexible diaphragm secured at its periphery to said tank along the length thereof, and having a central portion engageable at one side thereof with the internal contour of one of said tank ends, said one diaphragm side including a series of elongated ribs directly engageable with the internal contour of said one tank end and extending generally axially of said tank and converging near the port in said one tank end, and each operative to space the adjacent non-ribbed portion of the diaphragm from the interior surface of the tank to vent to such port any entrapped pocket which may tend to form.

5

2. Fluid discharge apparatus for discharging a fluid comprising:

- (a) a rigid tank having a fluid port at a first end to receive and to discharge the fluid, and having a pressurizing port at the opposite end, said tank ends each having an internal contour; and
- (b) a molded reversible flexible diaphragm secured at its periphery to said tank along the length thereof, and having a central portion alternatively engageable at opposite sides thereof with the internal contours of said tank ends, each of said diaphragm sides including a series of elongated ribs respectively directly engageable with the internal contours of said tank ends and each series extending generally axially of said tank and converging near the port in the adjacent tank end, and each series being operative to space the adjacent non-ribbed portion of the diaphragm from the interior surface of the tank and to vent to such port any entrapped pocket which may tend to form.

10

3. Fluid discharge apparatus for discharging a fluid comprising:

- (a) a rigid tank having ports at opposite ends;
- (b) a rigid cylindrical ring spotwelded to the interior of said tank, and having a bead at one axial end projecting in an axial direction therefrom and disposed in radially inwardly offset relation to the spotwelded portion of the ring and in radially inwardly spaced relation to the interior of the tank; and
- (c) a molded flexible diaphragm dividing said tank into two separate chambers, and having an integral bead received between said ring bead and the interior surface of said tank, said diaphragm also having an integral peripheral tapered lip adjacent to said bead and disposed within one of said chambers, said lip forming a seal with the interior chamber-defining surface of said tank.

20

4. Fluid discharge apparatus for discharging a fluid comprising:

- (a) a rigid tank jointly defined by a pair of cup-shaped tank end portions directly abutting each other at their mouths, each of said end portions having a port;
- (b) a separate rigid cylindrical ring within said tank directly engaging both of said abutting mouths, and having a bead at one axial end projecting in an axial direction therefrom disposed in radially inwardly offset relation to said ring and in radially inwardly spaced relation to the interior surface of said tank;
- (c) a spotweld seam spanning the mouths of said end portions along the line of abutment and forming a fluid seal directly between both of said mouths and said ring; and
- (d) a molded flexible diaphragm dividing said tank into two separate chambers, and having an integral bead received between said ring bead and the interior surface of said tank, said diaphragm also having an integral peripheral tapered lip adjacent to said bead and disposed within one of said chambers, said lip forming a seal with the interior chamber-defining surface of said tank.

45

5. Fluid discharge apparatus for discharging a fluid comprising:

- (a) a rigid tank having a fluid port at a first end to receive and to discharge the fluid, and having a pressurizing port at the opposite end, each of said tank ends having a substantially identical internal contour; and
- (b) a molded flexible diaphragm having a periphery secured to the interior of said tank, said diaphragm having a reversible central portion with an as-molded configuration which is substantially the same as said internal contour, and which is pressurizable into engagement at opposite sides thereof with substantially

70

75

the entire internal contour at each of said tank ends, each of said diaphragm sides including a series of elongated ribs respectively directly engageable with the internal contours of said tank ends and each series extending generally axially of said tank and converging near the port in the adjacent tank end, and each series being operative to space the adjacent non-ribbed portion of the diaphragm from the interior surface of the tank and to vent to such port any entrapped pocket which may tend to form.

6. Fluid discharge apparatus for discharging a fluid comprising:

- (a) a rigid tank including an internal contour at one end having means adapted to receive and discharge the fluid, and including a substantially identical internal contour at the opposite end;
- (b) means welded to the interior of said tank and defining a rigid bead disposed in radially inwardly spaced relation to the interior of the tank;
- (c) a molded flexible diaphragm having an integral peripheral bead received between said rigid bead and the interior surface of said tank, said diaphragm having a reversible central portion with an as-molded configuration which is substantially the same as said internal contour, and dividing the interior of said tank into two chambers, at least one side of said central portion being engageable with one of said internal contours, said one side including a series of elongated ribs directly engageable with said one of said internal contours and extending generally axially of said tank and converging toward said fluid receiving and discharging means, and each operative to space the adjacent non-ribbed portion of the diaphragm from the interior surface of the tank to vent any entrapped pocket which may tend to form; and
- (d) means for pressurizing the chamber adjacent to said opposite end.

7. Fluid discharge apparatus for discharging a fluid comprising:

- (a) a rigid tank including an internal contour at one end having means adapted to receive and discharge the fluid, and including a substantially identical internal contour at the opposite end;
- (b) means welded to the interior of said tank and defining a rigid bead disposed in radially inwardly spaced relation to the interior of the tank;
- (c) a molded flexible diaphragm having an integral peripheral bead received between said rigid bead and the interior surface of said tank and having a tapered lip resiliently acting against said interior surface and forming a seal therewith, and said diaphragm having a reversible central portion with an as-molded configuration which is substantially the same as said internal contour, and dividing the interior of said tank into two chambers within one of which said tapered lip is disposed, opposite sides of said central portion being alternatively engageable

with said internal contours, each of said sides including a series of elongated ribs respectively directly engageable with said internal contours and each series extending generally axially of said tank and converging toward said fluid receiving and discharge means, and each series being operative to space the adjacent non-ribbed portion of the diaphragm from the interior surface of the tank and to vent any entrapped pocket which may tend to form; and

- (d) means for pressurizing the chamber adjacent to said opposite end.

8. Fluid discharge apparatus for discharging a fluid comprising:

- (a) a rigid tank jointly defined by a pair of cup-shaped tank end portions directly abutting each other at their mouths, each of said end portions having a port;
- (b) a separate cylindrical ring within said tank directly engaging both of said end portions along said abutting mouths, and having an edge at one axial end projecting in an axial direction therefrom disposed in radially inwardly spaced relation to the interior surface of said tank;
- (c) a welded seam spanning the mouths of said end portions along the line of abutment and forming a fluid seal directly between both of said mouths and said ring; and
- (d) a molded flexible diaphragm dividing said tank into two separate chambers, and having an integral edge portion received between said ring edge and the interior surface of said tank.

9. Fluid discharge apparatus for discharging a fluid comprising:

- (a) a rigid tank having ports at opposite ends;
- (b) a rigid cylindrical ring welded to the interior surface of said tank, and having an edge at one axial end projecting in an axial direction therefrom and disposed in radially inwardly offset relation to the welded portion of the ring and in radially inwardly spaced relation to the interior surface of the tank; and
- (c) a molded flexible diaphragm dividing said tank into two separate chambers, and having an integral edge portion received between said ring edge and the interior surface of said tank.
